UNITED STATES PATENT OFFICE

VICTOR H. HARBERT, OF SPRINGFIELD, ILLINOIS

RETAINING-VALVE BRACKET

Application filed September 8, 1925. Serial No. 55,193.

5 Retaining valves are applied to cars to make the movement of a train of cars safe, and to conserve the supply of air, and this valve when set and in good working order does not allow all of the air to escape from the brake cylinder, but retains a certain amount of pressure therein sufficient to hold the brakes in a set position, while the air is being replenished in the train line. When 10 the air pressure in the line is increased or replenished, if the retaining valve is in an inoperative condition, the triple valve will automatically assume a released position allowing the train to gain momentum and run out of control. It is, therefore, of the utmost 15 importance that the retaining valve be in good working order at all times.

20 The practice in vogue prior to my invention was to bolt the retaining valve through the car end wall, but this practice has been found objectionable in that the bolt holes in the car wall gradually increase in diameter, due to the service movements of the car, whereby the bolts become lose, thus leaving 25 the valve and its pipe free to swing, thereby reducing the efficiency of the valve.

When the retaining valve becomes defective, it is necessary to remove the bolts from the inside of the car whether it be a house 30 car or open car, and if the car happens to be loaded, the load must be removed.

The object of my invention is to provide 35 an anchor for a retaining valve so mounted on the car and of such construction that the retaining valve may be detached from and applied to the anchor without removing the lead from the car, thereby reducing the expense of repairs to a minimum, and eliminating the possibility of damage and loss of the 40 contents of the car.

In the drawings:

Figure 1 is a front elevation of my anchor or bracket with a retaining valve secured thereto.

45 Figure 2 is a side elevation of Figure 1.

Figure 3 is a front elevation of my improved anchor or bracket.

Fig. 4 is a sectional view taken on the line 4—4 of Figure 3.

Fig. 5 is a top plan view of Figure 3.

The reference numeral 1 designates the air pipe, forming part of the air brake system of the car, to the upper end of which is secured the retaining valve 2, which is provided with the lugs or ears 3 having bolt or rivet 50 openings therethrough.

55 My improved anchor or bracket comprises a base plate 4 having at its upper edge a spacing member or shelf 5 extending forwardly and at right angles to said base. An apron 6 depends from the outer edge of the shelf and is spaced from and parallel to the base, but does not extend to the bottom edge of the base, as more clearly seen in Figures 2 and 4. Through the base and below the lower edge 60 of the apron are bolt or rivet holes 7 through which bolts or rivets pass to secure the anchor 65 to the car wall.

In the shelf 5, I form rectangular openings 8 through which the head 9 of bolts 10 may 70 pass, and there being a slot 11 in the shelf 5 communicating with these openings 8, to permit the passage of the body of the bolts into the elongated slots 12 formed in the apron 6, whereby the bolt heads 9 may pass down between the apron 6 and base 4 as clearly shown in Fig. 2.

75 The anchor is secured firmly to the car wall. In attaching the retaining valve to the anchor the bolts may be positioned loosely in 80 the slots 12 and when the valve is in proper position, the bolts are aligned with the holes in the ears 3 and the valve then pushed onto the bolts and the nuts 13 screwed tightly on the bolts, firmly securing the valve to the anchor. It will be noted that all operations necessary to attach or remove the valve from the 85 car are performed outside of the car.

In the first installation, the bolts 10 are 90 firmly secured near the top of the slots 12 so

that, in the event of any shortening of the pipe 1, due to breakage, re-threading, etc., of the pipe, the bolts 10 may be lowered in the slots to take care of any variations of length in the pipe, within reasonable limits, without disturbing the original position of the anchor.

What I claim is:—

1. A retaining valve anchor comprising a base, an apron extending downwardly from the top of and spaced from and parallel with and terminating short of said base, elongated slots in said apron opening at the top of said apron.

15 2. A retaining valve anchor comprising a base, an apron extending downwardly from the top of and spaced from and parallel with said base, and terminating short of the bottom of the base, elongated slots in said apron opening at the top of the apron.

20 3. A retaining valve anchor comprising a base, a shelf at the top of said base and extending forwardly from the base, an apron depending from the outer edge of said shelf but terminating short of the bottom of the base, said apron being parallel with said base, elongated slots in said apron, terminating in enlarged openings in said shelf.

25 4. A retaining valve anchor, comprising a base adapted to be secured to a support, a spacing member extending forwardly from the top of said base, and a plate depending from said spacing member and spaced from the base, said plate being adapted to support a retaining valve.

30 5. A retaining valve anchor, comprising a base adapted to be secured to a support, a spacing member extending forwardly from the top of the base, and a retaining valve supporting plate depending from said spacing member and spaced from the base and terminating short of the bottom edge of said base.

35 6. A retaining valve anchor, comprising a base adapted to be secured to a support, a spacing member extending forwardly from the top of said base, a retaining valve supporting plate depending from said spacing member and spaced from the base and bolt openings to receive bolts whereby the retaining valve is secured to said plate.

40 7. A retaining valve bracket comprising a base portion adapted to be secured to a support, a spacing portion extending forwardly from one of the horizontal edges of the base portion, and a valve attaching portion extending from the spacing portion in lapping spaced relation with the base portion, and means in said attaching portion for receiving the anchor bolts.

45 8. A retaining valve bracket comprising a substantially U-shaped plate, one side of the plate being extended beyond the plane of the perimeter of the other side, said extended portion being apertured to receive bolts for securing the bracket to a support, and means

in the other side of the plate for receiving the valve anchor bolts.

9. A retaining valve bracket comprising an inverted U-shaped member, one leg of the member being extended beyond the plane of the perimeter of the other leg and having apertures to receive bolts for securing the bracket to a car wall, while the other leg of the member is apertured to receive valve anchor bolts.

In testimony whereof I affix my signature.

VICTOR H. HARBERT.
